US00D995485S

(12) **United States Design Patent** (10) **Patent No.:** **US D995,485 S**
(45) **Date of Patent:** **** Aug. 15, 2023**

(54) **CONTROLLER**

(71) Applicant: **Meta Platforms Technologies, LLC**,
Menlo Park, CA (US)

(72) Inventors: **Yi-yaun Chen**, Seattle, WA (US);
Lorenz Henric Jentz, Seattle, WA (US); **Jason Andrew Higgins**, Seattle, WA (US); **Scott Andrew Dallmeyer**, Seattle, WA (US)

(73) Assignee: **Meta Platforms Technologies, LLC**,
Menlo Park, CA (US)

(**) Term: **15 Years**

(21) Appl. No.: **29/750,493**

(22) Filed: **Sep. 14, 2020**

(51) LOC (14) Cl. **14-03**

(52) U.S. Cl.

USPC **D14/218**; D21/333

(58) **Field of Classification Search**

USPC D14/156, 218, 430, 496; D21/333, 13, D21/27, 324, 328, 329-331, 325;

D18/4.4, 6, 7; D19/59, 60, 113;

D24/186; D10/104.1, 50, 65, 758;

D13/168

CPC A63F 13/23; A63F 13/24; A63F 13/25; A63F 13/218; A63F 2300/1087

See application file for complete search history.

(57) **CLAIM**

The ornamental design for a controller, as shown and described.

DESCRIPTION

FIG. 1 is a front perspective view of a controller showing the claimed design;

FIG. 2 is a rear perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines shown in the figures illustrate portions of the controller that form no part of the claimed design.

1 Claim, 8 Drawing Sheets
